UNITED STATES PATENT OFFICE

152,336

DESIGN FOR A LAMP

Stella J. Hirshfield, New York, N. Y.

Application March 1, 1947, Serial No. 137,266

Term of patent 14 years

(Cl. D48—4)

To all whom it may concern:

Be it known that I, Stella J. Hirshfield, a citizen of the United States, residing in New York, in the county of New York and State of New York, have invented a new, original, and ornamental Design for a Lamp, of which the following is a specification, reference being had to the accompanying drawing. The drawing is constituted as follows:

Fig. 1 is a perspective view of a lamp, showing my new design, and

Fig. 2 is a side view, partly in section, of a lamp, showing my new design.

I claim:

The ornamental design for a lamp, as shown.

STELLA J. HIRSHFIELD.
